CLAIM

The ornamental design for a phone case, as shown and described.

DESCRIPTION

FIG. 1 is a front, left side and bottom perspective view of a phone case, showing my new design;

FIG. 2 is a rear, right side and bottom perspective view thereof;

FIG. 3 is a rear, left side and top perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a front, right side and top perspective view of the phone case, where the phone case is in a first configuration of use;

FIG. 11 is a front, right side and top perspective view of the phone case, where the phone case is in a second configuration of use;

FIG. 12 is a front, right side and top perspective view of the phone case, where the phone case is in a third configuration of use;

FIG. 13 is a front, right side and top perspective view of the phone case, where the phone case is in a fourth configuration of use;

FIG. 14 is a front, right side and top perspective view of the phone case, where the phone case is in a fifth configuration of use;

FIG. 15 is a front, right side and top perspective view of the phone case, where the phone case is in a sixth configuration of use; and,

FIG. 16 is a partial enlarged view of portion 16 shown in FIG. 13.

The dash-dash broken lines in the drawings depict portions of the phone case that form no part of the claimed design. The dot-dash broken line circles in FIGS. 13 and 16 are provided for the purpose of indicating the portion included in the partial enlarged view and form no part of the claimed design.

1 Claim, 16 Drawing Sheets
